2,070,910

MECHANICAL OPERATION OF SMELTING FURNACES

Hugh R. MacMichael, El Paso, Tex., assignor to
American Smelting and Refining Co., New York,
N. Y., a corporation of New Jersey

Application July 26, 1928, Serial No. 295,419

9 Claims. (Cl. 266—10)

The invention relates in general to the art of metallurgy and, more particularly, to apparatus for mechanically operating a metallurgical hearth.

5 According to one form which the invention may take, a Scotch hearth such as used in lead smelting is provided with a carriage which is arranged to move step-by-step therealong and have mounted thereon various operating mechanisms, such as a mechanical poker and a mechanical shovel, to rabble and spread respectively the material in the hearth.

Suitable devices are provided to automatically stop and start the carriage and operating mechanism at the ends of the hearth and the step-by-step mechanism is arranged so that the carriage has substantially no movement while the shovel and poker are operating upon the hearth.

A particular mechanical shovel which may be employed is disclosed in application Serial No. 196,304, filed June 3, 1927, and a particular mechanical poker mechanism which may be employed is disclosed in application Serial No. 200,523, filed June 22, 1927.

25 The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a side elevation of the carriage and a section through the hearth;

Fig. 2 is an elevation of the carriage looking toward the back of the hearth;

Fig. 3 is a top plan view of the carriage illustrating the control mechanism;

Figs. 4 and 5 are further details illustrating the control mechanism; and

45 Fig. 6 is a detail illustrating one of the clutches.

In the following description and in the claims parts will be identified by specific names for convenience, but they are intended to be as generic in their application to similar parts as the art will permit.

Like reference characters denote like parts in the several figures of the drawings.

In the drawings accompanying and forming part of this specification, a practical commercial embodiment of the invention is shown, but

as such illustration is primarily for purposes of disclosure, it will be understood that the structure may be modified in various respects without departure from the broad spirit and scope of the invention as hereinafter defined and claimed.

Referring now to the drawings, and more particularly to Fig. 1, so much of a Scotch lead smelting hearth as is necessary to an understanding of this invention will be described. The Scotch hearth may comprise the usual basin or trough 1, the trough being comparatively narrow and relatively long, as is well understood. At the front edge of the trough, an apron 2 is provided extending the length of the trough, the apron sloping forward and slightly downwardly. At the back side of the trough and extending the length thereof is a back made up of a block 3 having a suitable water space 4 therein for cooling, underneath which are suitable tuyères 5 for supplying draft to the furnace, as is well understood in the art. A hood denoted generally by 12 is provided, its lower end being disposed close to the hearth efficiently to catch the fume and gases. This construction is well known and no further description is deemed necessary.

Disposed in front of the hearth overhead is a pair of rails 11 on which the carriage runs. The carriage comprises a suitable framework in which is journaled a pair of axles 6 and 7 which have mounted thereon wheels 8 running on the rails 11. The carriage carries the mechanical poker 9 and the mechanical shovel 10, which will be described in detail hereinafter.

The carriage is driven and motion is imparted to the shovel 10 and poker 9 by an electric motor 15. This motor drives a counter shaft 16 suitably journaled in the frame of the carriage and carrying a fly-wheel 17. This shaft also carries a spur gear 18, meshing a pinion 19 on the motor shaft, and also carries a pinion 20 driving a large spur gear 21 loosely mounted on the operating shaft 22. Mounted on a sleeve, which is secured to the spur gear 21, is a sprocket 23 supporting a chain 24 which is also supported on an upper sprocket 25 mounted on an upper shaft.

The operating shaft 22 is suitably journaled in the frame and carries in overhanging relation a cam wheel 28 in which is journaled a suitable buckle or clamp 29 for carrying the poker 9. Secured to the operating shaft 22 is a sheave of an eccentric, the strap 30 of which is connected to a rod 31 pivoted to lever 32 by pivot 33.

Secured to the spur gear 21 is one element 34 of a clutch 27 having suitable teeth, the other ele-

ment 35 of the clutch having teeth meshing therewith. The second clutch element 35 is feather keyed by key 36 to the operating shaft 22, being free to move longitudinally thereon, but constrained to rotate therewith. A suitable abutment 37 is on the operating shaft between which and the clutch element 35 springs 38 are provided to continually urge the teeth of the clutch elements into meshing relation.

10 To operate the clutch, the clutch element 35 is provided with a cam surface 39. A suitable lever 40 is pivoted by pivot 41 to the frame and is slidably mounted between guides 42. The lever 40 is provided with a cam follower 43 cooperating 15 with the cam surface 39. The lever 40 is connected to a vertical rod 44 extending upwardly to a lever 45, pivoted to the frame by pivot 46. The other end of the lever 45 supports a weight 47.

Secured to one axle 6 of the carriage is a ratchet 20 wheel 48. Straddling the ratchet wheel and loosely mounted on the axle is a pawl holder 49 to which is suitably pivoted the pawl 50. The pawl 50 is adapted to engage a shield 52 mounted on the end of a bell-crank lever 53, which is also 25 loosely mounted on the axle 6. The lever 53, is connected by rod 55 to a lever 54 which is fixedly mounted on the shaft 46. The pawl holder 49 has secured thereto an arm 56 which is connected to a link 57 which in turn is connected to a small 30 connector 58 connected to the lever 32 to allow universal motion. The adjustment lever 32 is provided with a plurality of holes to which the eccentric rod 31 may be selectively connected to change the throw of the pawl 50 and hence the 35 distance the carriage is moved with each revolution of the eccentric.

The upper shaft 100 is suitably journalled in the carriage frame and carries a clutch element 101 of clutch 117 loosely mounted thereon to which 40 is secured the upper sprocket 25. The other clutch element 102 is feather-keyed to the shaft and is normally held in disengaged position by the spring 103. The shaft 100 is geared to the axle 7 by bevel gears 104 and 105.

45 To control the mechanism for driving the carriage, so that it may advance step-by-step on its operating trip or pass and return by continuous movement on its return trip, suitable control linkage is provided.

50 Disposed along the tracks 11 is a control rail 106 having its ends 107 turned away from the carriage. Suitably pivoted by pivot 108 to the carriage is a control lever 109 having a roller 110 at its outer end. The control lever 109 is also pivoted to the clutch collar of clutch element 102 by pivot 111. A short lever 112 is pivoted to the frame by pivot 113, and a long lever 114 is pivoted to the frame by pivot 115. The short lever is connected to pivot 111 and to the long lever by 60 pivot 116.

Disposed along the tracks 11 at the end of the operating pass or trip is a long stationary rod 118 on which is slidably mounted a contact member 119 and fixedly mounted a stop 120. A long 65 coil spring 121 is disposed between the contact member and stop. The rod 118 is provided with a second stop 122 for limiting the expansion of the spring.

70 Referring now to the poker 9, a fulcrum support 123 is provided on the frame for supporting the poker at a point near the edge of the trough 1. Pivottally connected to the buckle 29 is a grooved roller 124.

75 Referring now to the mechanical shovel, the framework of the carriage is provided with a pair

of lugs or ears to which the impeller arm 60 is pivotally connected by pivot 61 and a second pair of spaced ears to which a composite lever 62 (Fig. 2) is pivoted by pivot 63. The framework has a bracket member 64 having aligned openings in which is slidably mounted a follower rod 65 having at its lower end a roller 66 engaging the cam surface 125 on the cam wheel 28.

The follower rod 65 is provided with a suitable abutment 68 between which and the plate 69 10 is disposed a coil spring 70, this coil spring acting to continuously urge the follower rod against the cam surface. The plate 69 is secured in fixed relation to the bracket member by a pair of rods 71 disposed on either side of the follower 15 rod.

As shown, the impeller arm 60 is curved at its upper end and generally straight for the rest of its length and has secured to one side thereof a pair of spaced lugs 72. A pair of spaced 20 ways or guides 73 is secured to the lugs, these ways or guides being curved, as shown in Fig. 1, to aid in giving the desired peculiar motion 25 to the shovel blade 74. The grooved roller 124 on the buckle is disposed between these ways.

Pivoted at the lower end of the impeller arm is a shovel arm 77, this arm comprising a body member having an opening in its middle portion, forming branches (Fig. 2) between which the lower end of the impeller arm is disposed. A suitable pivot bolt 78 threads the branches and the impeller arm. The front end of the body is suitably forked, and between the prongs of the fork the lower end of the elevating link 79 is suitably pivoted by a pivot bolt 80. The rear 35 end of the shovel arm is provided with the blade 74 of the shovel which extends longitudinally of the furnace a substantial extent and has a slightly back-curved lower end 81, as shown in Fig. 1.

The upper end of the elevating link 79 has a 40 suitable loose or universal connection 126 with the composite lever 62 to allow the swinging movement of the elevating link back and forth and the up-and-down movement imparted thereto by the composite lever. The follower 45 rod 65 has a pivot 83 which works in a slot in the composite lever 62 so that the reciprocating movement of the follower may be imparted to the composite lever.

The carriage is shown in Fig. 3 almost at the 50 end of its operating trip or pass. The clutch 117 is normally held disengaged by the spring 103 and the control lever 109 rides idly along the control rail. The clutch 27 is engaged and the shovel 10 and poker 9 are being continuously 55 operated; also the ratchet 50 is being reciprocated to move the carriage step-by-step. The parts are so related, however, that all movement of the carriage takes place when the poker and shovel are out of the charge in the hearth, so 60 that, while the poker and shovel operate on the charge in the hearth the carriage is stationary.

As the carriage approaches the end of its operating pass or trip, the long lever 114 engages the contact member 119 and compresses the spring 121 as shown in Fig. 3. As soon as the control lever 109 rides off the end of the rail 106, the clutch 117 is engaged, since the spring 121 through the linkage 112, 114 exerts enough force to overcome the clutch spring 103. At the same 70 time the clutch 117 is engaged, the levers 45, 54 and rods 44, 55 are moved (1) to place the shield 52 under the pawl 50, so that the pawl oscillates idly and (2) to move the lug 43 in the path of the cam surface 39, so that the clutch 27 dis- 75

engages itself. The cam 39 and the pressure of springs 38 are so arranged that, when the clutch 27 disengages, it disengages with the cam in such position, that the poker and shovel are out of the hearth.

Under the action of the clutch 117, the carriage begins a continuous return movement, the long spring 121 holding the clutch 117 engaged until the control lever 109 again engages the control rail, whence it holds the clutch 117 engaged.

When the carriage reaches its starting end, the control lever 109 again rides off the control rail, and the clutch spring 103 automatically disengages the clutch, and, operating upon levers 45, 54 and links 44, 55, removes the shield 52 from beneath the pawl 50 and the lug 43 from the cam face 39. This allows the clutch 27 to engage and the carriage to advance once more with a step-by-step movement. It will be noted the mechanical connection between the poker and shovel and step-by-step mechanism is continuous and permanent so that there is always a constant relation between the poker and shovel and the position of the ratchet, thus insuring that the carriage is always stationary while the poker and shovel are in the hearth.

The end of the poker 9 will describe a closed path and the charge will be broken up and leveled down and parts of the charge thrown on the apron, all as is described in the above copending applications. The top of the charge, when thus leveled down, under some conditions is illustrated by line 86 in Fig. 1.

35 The mechanism will cause the shovel to execute a movement illustrated by the dotted line and arrows indicated by 87 in Fig. 1. This shovel will scrape the apron, as shown, and push the charge back, forming the bank which, under 40 some conditions may be illustrated by the line 88 in Fig. 1. The shovel will travel slowly at the front of the hearth but will receive a sudden flip about halfway across the basin which flips the material up against the back of the hearth 45 and causes it to roll forward by gravity, providing a selective action, as explained in the above copending applications.

When the poker engages the charge, it breaks up the charge and levels it down and throws 50 part of it on the apron, similar to the old manual operation. The shovel following pushes the charge back, flipping part of it against the furnace back and causing part of it to roll forward with a selective action. The larger particles roll 55 forward the furthest and particles of slag roll down on the apron, from which they can easily be removed. A feeder (not shown) may follow the shovel to feed the charge (which, in the case of lead ores, may be pre-mixed fuel, ore and 60 fume) in such manner as to get the proper distribution across the width of the hearth, or the charge may be fed by hand by workmen as in the old and well-known manner.

65 By means of the carriage with its above described operating mechanisms and its automatic control features, a Scotch hearth type of furnace or other furnace may be operated substantially automatically to a large degree. The automatic mechanism furthermore insures the proper starting and stopping of the poker and shovel and proper operation of the carriage. By the use 70 of the present invention the operation of a Scotch hearth may be made substantially uniform and when adjustment has been made to obtain the

best operating conditions, the device insures continuance of these conditions.

While certain novel features of the invention have been shown and described and are pointed out in the annexed claims, it will be understood 5 that various omissions, substitutions and changes in the forms and details of the device illustrated and in its operation may be made by those skilled in the art without departing from the spirit of the invention.

10 What is claimed is:

1. In apparatus of the class described, a furnace, a trackway along said furnace, a carriage on said trackway adapted to make operating trips and return trips, a first means on said carriage to drive it on its operating trip, a means on said carriage to drive it on its return trip, interlocking devices for selectively causing said means to drive said carriage, biased means normally causing one means to drive said carriage and holding 20 the other means inoperative, means operable at the end of one of said trips of said carriage for interchanging said driving means, and means along said trackway for holding said driving means in interchanged condition till the carriage 25 reaches the end of its other trip.

2. In metallurgical apparatus, a lead smelting hearth having a relatively long and narrow trough, a carriage adapted to move back and forth along said hearth, a poker and shovel on said carriage for operating said hearth, driving means for imparting a step-by-step movement to said carriage on its operating trip and for operating said poker and shovel only when said carriage is substantially stationary, driving means 30 for imparting a continuous movement to said carriage on its return trip with said poker and shovel clear of said hearth, and devices operable at the ends of said trips for automatically exchanging said driving means.

3. In combination with a furnace, a support, a drive shaft on said support, a cam wheel secured to said shaft, a holder pivoted to said wheel, a poker in said holder, a fulcrum for said poker near said furnace, an impeller arm pivotally connected to said support, a transverse lever pivoted to said support, an elevating link pivoted to said lever, a shovel arm pivoted to said impeller arm and elevating link, a follower riding on said cam wheel and pivoted to said lever, a guide for said follower, a guideway secured to said impeller arm, and a guide member cooperating with said guideway and secured to said holder.

4. In combination with a furnace, a support, a drive shaft on said support, a cam wheel secured to said shaft, a holder pivoted to said wheel, a poker in said holder, a fulcrum for said poker near said furnace, an impeller arm pivotally connected to said support, a transverse lever pivoted to said support, an elevating link pivoted to said lever, a shovel arm pivoted to said impeller arm and elevating link, a follower riding on said cam wheel and pivoted to said lever, a guide for said follower, spaced ways secured to said impeller arm, and a guide wheel between said ways and secured to said holder.

5. In combination with a smelting hearth having a relatively long and narrow basin, a trackway along said basin, a carriage on said trackway, means for imparting a step-by-step motion to said carriage, a poker on said carriage to poke into the charge, a shovel on said carriage for pushing back part of the charge, and means for causing said shovel and poker to operate simul- 70 75

taneously on different parts of the charge only while the carriage is substantially stationary.

6. In apparatus of the class described, a furnace, a trackway along said furnace, a carriage on said trackway, a drive motor on said carriage, drive wheels on said carriage, a first clutch between said drive motor and drive wheels, an operating shaft, a crank on said shaft, operating devices connected to said shaft for operating said furnace, a second clutch between said motor and operating shaft, drive connections between said operating shaft and said wheels, means for normally holding said first clutch disengaged and said second clutch engaged, a control rail along said trackway, a control member secured to said carriage and adapted to ride on said rail to hold said first clutch in engagement on the return trip of said carriage, linkage connecting said control member and clutches, devices at the end of the trackway whereby, at the end of the operating trip, said linkage causes the first clutch to engage as soon as the control member runs off the rail and opens said second clutch.

7. In apparatus of the class described, a furnace, a trackway along said furnace, a carriage on said trackway, a drive motor on said carriage, drive wheels on said carriage, a ratchet wheel connected to one of said drive wheels, a clutch connected to another of said drive wheels, an operating shaft, operating devices connected to said shaft for operating upon said furnace, a pawl operating on said ratchet wheel, connections directly from said operating shaft to reciprocate said pawl to drive said carriage step-by-step on its operating trip, drive connections from said motor to said clutch, a second clutch on said operating shaft for controlling said operating shaft and driven by said motor, said first clutch having a spring holding it normally disengaged, a control rail along said trackway, a control lever pivoted to said carriage and to said first clutch and adapted to trail on said rail to hold said first clutch in engagement to drive said carriage continuously on its return trip, a shield, linkage connected to said lever, to said shield and to said second clutch, a slide at the end of the trackway, a contact member and a control spring on said slide, whereby, at the end of the operating trip, said linkage engages said contact member to compress said control spring to cause the first clutch to engage as soon as the control lever runs off the rail and to place said shield under said pawl and open said second clutch.

8. In apparatus of the class described, a furnace, a trackway along said furnace, a carriage on said trackway, a drive motor on said carriage, drive wheels on said carriage, a ratchet wheel connected to one of said drive wheels, a clutch connected to another of said drive wheels, an operating shaft, a crank on said shaft, a poker and shovel for rabbelling and spreading the charge respectively, connections between said crank and poker and shovel, a pawl operating on said ratchet wheel, connections directly from said operating shaft to reciprocate said pawl to drive said carriage step-by-step on its operating trip, drive connections from said motor to said clutch, a second clutch on said operating shaft for controlling said operating shaft and driven by said motor, said first clutch having a spring holding it normally disengaged, a control rail along said trackway, a control lever pivoted to said carriage and to said first clutch and adapted to trail on said rail to hold said first clutch in engagement to drive said carriage continuously on its return trip, a shield, linkage connected to said lever, to said shield and to said second clutch, a slide at the end of the trackway, a contact member and a control spring on said slide, whereby, at the end of the operating trip, said linkage engages said contact member to compress said control spring to cause the first clutch to engage as soon as the control lever runs off the rail and to place said shield under said pawl and open said second clutch.

9. In combination with a smelting hearth having a relatively long and narrow basin, a carriage, means for moving said carriage along said basin, a poker on said carriage to poke into the charge, a shovel on said carriage for pushing back part of the charge, means for causing said shovel and poker to operate on the charge, and means for causing said shovel and poker to partake of no substantial movement along said basin while operating on said charge.

HUGH R. MACMICHAEL.
